UNITED STATES PATENT OFFICE.

HUGH H. EBY, OF PHILADELPHIA, PENNSYLVANIA.

BINDING POST.

Application filed January 4, 1924. Serial No. 684,290.

To all whom it may concern:

Be it known that I, HUGH H. EBY, a citizen of the United States, residing at 3859 N. Gratz Street, Philadelphia, in the county 5 of Philadelphia and State of Pennsylvania, have invented certain new and useful Binding Posts, of which the following is a specification.

My invention relates to binding posts as 10 used in the electrical industry for securing an efficient electrical connection with electrical apparatus.

The main purpose of my invention is conveniently and effectively to prevent removal 15 of the contact cap from the binding post.

A further purpose is to protect the threads of the binding post from mechanical injury.

A further purpose is to provide a post 20 adapted to easy and inexpensive manufacture and to meet efficiently the needs of service.

Further purposes will appear in the specification and in the claims.

25 I have preferred to illustrate my invention by a few forms among the many in which it may be displayed, selecting forms which are practical, efficient and inexpensive and which at the same time well illustrate 30 the principles of my invention.

Figures 1 and 2 are vertical central sections through the upper (cap) and bottom contacts, respectively, used in my invention.

Figure 3 is a side elevation of the stem of 35 the binding post.

Figure 4 is a central vertical section showing the assemblage of the parts in Figures 1, 2 and 3.

Figure 5 is a bottom plan view of Figure 2.

Figure 6 is a broken side elevation and partial section showing the screw and contact cap with a molded cover insulating the cap.

45 Figure 6^a is a fragmentary view to reduced scale similar to Figure 6 but showing the form of Figure 4.

Figure 6^b is a fragmentary section corresponding to Figure 6 before the peening of 50 the flange.

Figure 7 is a bottom plan view of Figure 6.

Figure 8 is a side elevation showing a post with attaching parts.

55 Figure 9 is a side elevation, partly sec-

tioned, showing the lower contact member and molded cover of Figure 8.

Figure 10 is a bottom plan view of Figure 9.

Figure 11 is a vertical longitudinal section showing a slightly modified form.

In the drawings similar numerals indicate like parts.

The stem 15 of my binding post is shown as threaded at 16 for convenient nut attachment to any suitable support. It is provided with a lower contact member 17 which may be integral with the stem, as in Figure 11, or may be secured to it as by screwing the member upon the threads. 60 Ordinarily the member is sweated upon the thread at 18.

As the lower contact member in the illustration is preferably not full metal the diameter is reduced at 19 below that of the contact face 20, which is the upper face of a flange 21. The lower portion beneath the flange as at 22 is filled in by a molded base intended to afford a better rest upon the support, to reduce the metal required 75 and to give finish. This finish material is ordinarily an insulating composition. It is secured to the lower contact member against longitudinal movement by grooving the latter as at 23 to permit interlocking of the covering material with the contact member. Rotation may be stopped by flattening one side 80 as dotted at 20'.

The lower edge of the contact member extends below the "base" as at 24 and is 90 roughened in any suitable manner, as by the teeth shown, so as to bite into the surface of the support to which the binding post is to be applied, preventing turning of the binding post and giving a firmer and more rigid seat to the post. The under side of the lower contact member is also recessed at 25 for the purpose of facilitating application of the solder at the apex of the recess at 26.

100 The binding post may be held in position and engage the lower end of the support by nuts 27, 28. Between the nuts are located washers 29 so that the nut 27 may be fastened against the back or under side of the support and the nut 28 may be used for the double purpose of clamping the conductor between the washers 29, and acting as a lock nut for the nut 27.

105 Above the contact surface 20 the stem or 110

post is formed as a cylinder 30 which is apertured at 31 close to the surface 20 to permit passage of the conductor to be clamped. The stem may be encircled by a conductor if desired.

The cylindrical part 30 extends far enough to provide for any required opening between the clamping surface 20 and the clamping surface 32 upon the flange 33 of 10 an upper contact nut 34, like the lower contact member preferably not full metal and also to allow for an inwardly directed stop or abutment 35 between the surface 32 and the thread 36 upon the upper end of the 15 stem. This thread is appreciably larger than the cylindrical portion of the stem so as to provide for a shoulder 37 which engages with the shoulder of flange 35. Obviously whether the stop flange 35 directly 20 engages the lower end of the thread 36 or not is immaterial: it may engage a shoulder or flange such as 37' in Figure 6 or its function may be carried out by a removable stop held in place in the inner part of the cap 25 as in Figure 11, provided the lower part of the interior thread 38 of the cap can not be withdrawn through the bottom of the cap.

Where the metal of the upper and lower contact members is of small diameter, as to 30 give room for a decorative molded covering, the flanges 33 and 21 perform a useful function in presenting a larger contact area for the same diameter of body than would otherwise be available.

35 The thread 36 fits thread 38 within the cap so that the stem 15 may be passed into the cap from the open cap end. I have preferred to make the thread 38 sharp clear to the bottom of the opening against the 40 abutment 35 so as to be able to have a clearly defined shoulder 37 engage with the abutment 35 to stop upward screw movement of the cap contact member, rather than, for example, to have the thread 36 engage 45 against an abutment in the form of an insufficiently cut thread at the bottom of the cap recess.

Where the stem is intended to be passed through from the open end of the cap, as in 50 Figure 4, the lower contact member 17 must be a separate piece from the stem and must be attached after the cap has been placed upon the stem.

After the cap and stem have been assembled the top of the cap is closed and a molded insulating cover is placed about and upon the cap so as to provide for easy turning of the cap contact. The insulated cover may itself form the closure at the top 55 of the cap or a separate closure may be applied. In Figure 4 I show a separate closure comprising a plate 39 which is slipped into a recess 40 at the top of the cap and may be subsequently covered with the 60 molded cover. I find it more convenient to

70 snap the plate into a recess or press it into a recess in which it fits tightly in order that the plate may not fall out during the covering operation. The outer surface 41 of the upper contact member is knurled so as to give a firm hold upon it for the covering material.

75 The knurled upper contact member as described with its plate closure may be used without covering material to form an effective binding post. However, when covered with material 42 it forms a much more desirable hold for the user, both because of the insulation provided and because of the larger diameter given by the covering material. It may be finished as desired.

80 The construction shown protects the threads from exposure to dirt, grease, etc. and reduces opportunity for shock and for 85 injury to the fingers.

80 Instead of the plate 39 the molded insulation may be used to cover the top of the binding post and at the same time prevent withdrawal of the stem through the top of the cap or excessive upward movement of the stem within the cap. Either construction prevents accidental loss of the cap when the lower contact piece is not in place.

90 When a plate such as 39 is not used, the upper end 43 of the stem when in the position shown in Figure 6 may be used to close the open end of the cap opening while the insulation is being molded about the cap.

95 In Figure 6 I have shown a shoulder 37' 100 at a distance from the lower end of the thread at 37 as engaging the shoulder 35' at the inner end of the cap opening to prevent withdrawal of the cap contact outwardly from the stem. Obviously the purpose of what I have called a shoulder 35' 105 here may be served by any projection or interior thickening which will bar the passage of the threaded portion 36 or of any shoulder or enlargement upon it.

110 The flanges or abutments 35, 35', 35² etc., may be formed initially in the shape indicated, when the stem is to be inserted from the open (outer) end of the cap contact, or may be formed by the inward peening, rolling, crimping or compression of the lower 115 end of the cap, whether it be initially extended beneath the cap as at 35² (Figure 6^b) or not. In Figure 11 an enlarged lower opening in the cap is closed as at 44 by forcing a ring 45 into the enlarged opening and peening the flange or abutment slightly against the ring. In this case the flange must be turned in to leave a flat lower contact surface.

120 As thus constructed the upper (cap) contact member is given a range of movement sufficient for proper gripping of any conductor placed between its face and that of the lower contact. It provides a large 125 surface of contact and permits the use of a 130

straight conductor passing through the opening 31 or a bent conductor encircling the stem wholly or in part. At the same time removal of the cap from the stem is prevented and longitudinal movement is limited to any predetermined range desired.

In the form shown in Figure 6^b the stem is inserted from the inside of the cap and the flange 35^a is then peened over or 10 pressed as shown into the space beneath the thread of the screw so as to prevent removal of the screw.

In the form shown in Figure 11 the outer end of the cap contact member at 39' is 15 integral with the sides.

I recognize that the threads themselves may be used to afford stops for movement in either direction by crimping either of the threaded ends of the cap inwardly some- 20 what or not cutting them to the full depth to prevent its withdrawal therefrom. This form of stop at the outer end might be used in Figure 4, for example, without the plate 39 and without the molded cover, lacking somewhat, however, in finish and protection against intrusion of grit or other dirt or grease.

Whatever the form of stop provided within the cap to prevent relative movement of 30 the stem with respect to the cap so as to retain the cap, and whether the stop engages portions of the thread or independent shoulder structure carried by the stem, accidental removal of the cap is prevented.

35 The opening 31 may be of any shape desired and slight play between the thread 36 and the interior thread 38 may be provided to permit slight canting of the contact surface 32 with respect to the conductor to be 40 engaged where taper or irregularity of the conductor makes this canting desirable in order to ensure good contact along the entire length of this part of the conductor.

The comparatively close sliding contact 45 of the cylindrical portion 30 of the stem with the walls of the cap opening through which it passes protects against catching and shearing of fine wires and adds to the appearance of the post.

50 The sweating of the lower contact of the stem improves the electrical conductivity at the same time that it prevents shifting of this contact from its preferred position level with the bottom of opening 31.

55 This application is a continuation in part of my application for electrical binding posts, filed February 4, 1922, Serial Number 534,183.

It will be obvious that part or all of 60 the benefit of my invention may be secured by the use of other appliances and constructions than those shown, whether to suit special needs, to meet the views or whims of others skilled in the art or to avoid mere copying of the structure shown; and it is

my purpose to include herein all such as fall within the reasonable spirit and scope of my invention.

Having thus described my invention, what I claim as new and desire to secure by Letters Patent is:—

1. An electrical binding post stem terminating in a threaded portion of substantially uniform diameter and, at an intermediate point of smaller diameter than the 75 normal outside of the thread to form a shoulder adjacent the part of smaller diameter, a cap upon the stem overlapping the thread at both ends, internally threaded and adapted during use to operate upon the 80 thread of the stem in the performance of the clamping function and an interiorly directed portion upon the cap of smaller effective internal diameter than the normal outside of the thread on the cap to engage 85 the shoulder of the stem and prevent removal of the cap at the threaded end.

2. A binding post stem having threads at both ends, each of substantially uniform diameter and an intermediate section of 90 smaller diameter than the outside of the thread at the outer end and an outer clamping cap fitting the thread at the outer end, in use engaging this thread to perform the clamping function and at one end of the 95 cap of internal effective diameter smaller than the normal diameter of the thread at said outer end of the stem, the cap being closed at the opposite end to prevent access to the outer end of said stem. 100

3. A binding post stem having a thread at each end, one thread larger than the other and at an intermediate point reduced to a diameter smaller than the outside diameter of the larger thread, a clamping cap 105 adapted to be fitted on from the threaded end of the smaller diameter, always in use mounted upon the thread of larger diameter to perform the clamping function and an inwardly directed abutment upon the cap 110 extending toward the part of smaller diameter of the stem to provide a positive stop against axial movement, to prevent removal of the cap at the larger end, in combination with means for fastening the 115 threaded end of smaller diameter to a support.

4. A binding post stem having a substantially uniform thread at each end, one thread larger than the other, substantially 120 free from threads at an intermediate point and there of a diameter smaller than the outside of the larger thread, a cap adapted to be fitted on from the threaded end of the smaller diameter, continuously in use interthreading with the thread of larger diameter and having an inwardly directed abutment fitting close to the part of smaller diameter to prevent removal of the cap at the larger end and a closure for the outer 125 130

- end of the cap over the larger threaded end of the stem.
5. A binding post stem having one end enlarged and threaded, in combination with a cap threaded to engage and in use at all times engaging the threading of the stem and of reduced internal diameter adjacent its thread providing a positive stop to bar withdrawal of the stem thread through that end of the cap and having a contact face at the lower end of the portion of reduced diameter and a retaining device for the stem having a face for contact at its upper end to cooperate with the first face.
10. In an electrical binding post, a stem threaded at both ends, the threads at one end of the stem being of larger diameter than those at the other, in combination with a cap of smaller diameter at its inner end than the threads of larger diameter to provide a positive stop against removal, in use continuously interthreading with these threads, having a contact surface and adapted to be put on the stem from the end of smaller diameter, a closure for the end of the cap, a cover for the cap and closure insulating the cap and a fastening device for the stem having a second contact surface of extended size to receive a conductor.
15. 6. In an electrical binding post, a stem threaded at both ends, the threads at one end of the stem being of larger diameter than those at the other, in combination with a cap of smaller diameter at its inner end than the threads of larger diameter to provide a positive stop against removal, in use continuously interthreading with these threads, having a contact surface and adapted to be put on the stem from the end of smaller diameter, a closure for the end of the cap, a cover for the cap and closure insulating the cap and a fastening device for the stem having a second contact surface of extended size to receive a conductor.
20. 7. A binding post stem having a threaded outer end and a relatively reduced portion free from threads adjacent to the threaded outer end, in combination with a cap for said stem interfitting with the thread of the stem at all times in use and having a relatively reduced portion free from threads fitting close to that part of the stem free from threads and protecting against entanglement of the clamped conductor in the threads.
25. 8. A binding post stem having a threaded outer end and a relatively reduced portion free from threads adjacent to the threaded outer end, in combination with a cap for said stem interfitting with the thread of the stem at all times in use and having a relatively reduced portion extending toward that part of the stem free from threads to positively limit the movement of the cap toward the outer end.
30. 9. A binding post stem having a threaded outer end and relatively reduced and free from the threads adjacent to the threaded outer end, in combination with a cap for said stem interfitting with the thread at all times in use and extending towards that part of the stem free from threads to positively limit movement of the cap toward the outer end, a closure for the outer end of the cap and a cover for the cap and closure.
35. 10. A binding post comprising a threaded member having threads at both ends, that at the outer end being the larger, and an intermediate portion free from threads and of less effective diameter than the thread at the outer end, in combination with a cap interthreading with the thread on the outer end of the member at all times in use and extending towards the unthreaded portion and interiorly engaging with the stem to limit outward movement of the cap.
40. 11. In a binding post, a stem, a contact member intermediate its length, a thread at one end of the stem, means for circuit connection to the stem, a cap contact member internally threaded to engage the thread at the end of the stem at all times in use and a plate closing one end of the cap and positively retained within the cap contact member, said cap being inwardly extended at the other end to less than the normal diameter of the thread to prevent removal.
45. 12. An electrical binding post consisting of a stem terminating in a threaded portion and of reduced diameter and free from threads adjacent the threaded portion, forming a shoulder between the portion free from threads and the thread, and a clamping cap mounted upon the thread, extending axially beyond it at both ends, closed at the outer end and at the inner end radially reduced to less than the diameter of the thread to positively engage the shoulder and prevent removal of the cap over the thread of the stem.
50. 13. An electrical binding post stem including a threaded portion of larger diameter than the remainder of the post stem, having a portion free from threads adjoining the threaded portion so that the enlarged thread forms an annular shoulder to the outside of the portion free from threads, in combination with a clamping cap initially open at both ends, internally threaded to a greater axial length than the axial length of the thread upon the stem and having at its inner end an inwardly directed abutment of smaller internal diameter than the diameter of the shoulder to abut against the shoulder and positively prevent removal of the cap in an outward direction.
55. 14. In a binding post of the type having a stem threaded at one end, a contact member intermediate its length and means for circuit connection to the stem, the combination of a second thread located upon the other end of the stem, a shoulder between the thread upon the stem and the contact member, a cap having an opening through it which is internally threaded to fit and in use engages the thread on the end of the stem, a closure for the opening at the outer end of the cap and an abutment on the inner end of said cap of internal diameter smaller than the thread, adapted to engage the shoulder.
60. 15. In a binding post of the type having a stem threaded at one end, and an inner contact member threaded thereon, the combination of a cylindrical intermediate portion upon the stem, a thread at the other end

of larger diameter than the first and an outer contact member roughened upon its outer surface, interiorly threaded to constantly interthread with the larger thread 5 and inwardly extended at its inner end to a smaller diameter than its thread, providing for insertion of the stem and for positive engagement of the inwardly extended part on the cap with the stem axially to prevent 10 removal of the cap.

16. In a binding post of the type having an intermediate contact member, a thread upon the inner end of the stem and a nut thereon to hold a support between the nut 15 and contact member, the combination of a thread at the outer end of the stem larger than that at the inner end, a plain apertured cylindrical portion adjacent the larger thread and of smaller diameter than said 20 thread and an outer contact cap member internally threaded to engage and, in use, constantly engaging the larger thread of the stem, open initially at both ends and of diameter at the one end smaller effectively 25 than the thread but larger than the plain stem portion, fitting the plain portion and movable along its length.

17. In a binding post, a cap clamping member internally threaded and having a 30 portion free from threads at its inner end reduced in diameter below that of the largest diameter of the thread, a stem threaded at one end to engage with the interior thread of the cap, and in use constantly engaging 35 with it, adapted to be stopped from with-

drawal by the reduced diameter of the cap, of plain cylindrical shape below the cap at all operative heights of the cap and terminating at its other end in a threaded portion and a second contact member upon the stem 40 and extending to the plain cylindrical portion of the stem.

18. In a binding post, a stem enlarged at its outer end and threaded at the enlarged part, a cap contact member threaded to secure it upon the stem and cooperating parts comprising an abutment of reduced diameter and an axially facing shoulder respectively integral with the cap and integral with the stem limiting by direct engagement 50 with one another the outward motion of the cap with respect to the stem.

19. In a binding post of the type in which the stem carries a smooth cylindrical portion apertured to pass electric conductors, 55 and an inner contact member whose outer surface is substantially tangent to the edge of the aperture, the combination of a thread upon the stem to the outside of the inner contact member and smooth portion, a cap 60 contact member threaded thereon, adapted to screw toward and away from the first contact member and to clamp between the contact members any conductor passing through the aperture and cooperating parts 65 respectively carried by the cap and carried by the stem positively limiting by their engagement with one another the outward motion of the cap with respect to the stem.

HUGH H. EBY.
